UNITED STATES PATENT OFFICE.

ALFRED REDFERN, OF PHILADELPHIA, PENNSYLVANIA, ASSIGNOR TO VAN DEVENTER & HORNE, OF NEW YORK, N. Y.

DESIGN FOR A CARPET.

SPECIFICATION forming part of Design No. 13,126, dated August 1, 1882.

Application filed June 26, 1882. Term of patent 3½ years.

To all whom it may concern:

Be it known that I, ALFRED REDFERN, of Philadelphia, in the State of Pennsylvania, have invented a certain Improved Design for Carpets, of which the following is a specification.

The design of my pattern is represented in the accompanying photograph. This pattern is adapted to any character of carpet, whether woven as ingrain, three-ply, Brussels, or tapestry, and in any colors that may be desired.

The groundwork of the pattern is mottled with faint diagonal lines, forming diamond shapes with central spots, and the figure is composed of palm-leaf figures *a a*, arranged to form, with the leaflet-patterns *b b*, a general diamond configuration, leaving intermediate spaces for set patterns, one range of spaces being occupied by the bouquet-pattern *e*, com-

posed of stems, flowers, leaflets, and sprigs, 20 and the other range of spaces being occupied by the leaflet and Grecian scroll and stems, as at *f*. These patterns are reproduced in regular succession, so that the patterns on one breadth of carpet match with and are continued on the next.

I claim as my invention—

The design for carpets, consisting of the palm-leaf patterns *a* and leaflets *b*, arranged, as shown, with the bouquet-patterns *e* and the 30 leaflet and Grecian-scroll patterns *f*, placed alternately, as described and represented.

Signed by me this 16th day of June, A. D. 1882.

ALFRED REDFERN.
